(57) **CLAIM**

The ornamental design for a multiple purpose utility tool, as shown and described.

DESCRIPTION

FIG. 1 is a front, bottom, and right side perspective view of the multiple purpose utility tool showing my new design. FIG. 2 is a rear, top, and left side perspective view thereof. FIG. 3 is bottom plan view thereof. FIG. 4 is a top plan view thereof.

FIG. 5 is a right side elevational view thereof.

FIG. 6 is a left side elevational view thereof.

FIG. 7 is a front elevation view thereof; and, FIG. 8 is rear elevation view thereof.

The broken lines shown in FIGS. 1-8 depict environmental subject matter, are for illustration only, and form no part of the claimed design.
